UNITED STATES PATENT OFFICE.

CORNELIA M. POST, OF LANGHORNE, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR LINOLEUM, OILCLOTH, OR FLOOR COVERING.

60,427.

Specification for Design.

Patented Feb. 14, 1922.

Application filed December 13, 1921. Serial No. 522,167. Term of patent 14 years.

To all whom it may concern:

Be it known that I, CORNELIA M. Post, a citizen of the United States, and a resident of Langhorne, in the county of Bucks and State of Pennsylvania, have invented a new, original, and ornamental Design for Linoleum, Oilcloth, or Floor Covering, of which the following is a full, clear, and exact description, reference being had to the accompanying drawing, forming part of this specification.

The figure is a plan view of a piece of linoleum embodying my design.

I claim:

The ornamental design for linoleum, oilcloth or floor covering as shown.

CORNELIA M. POST.
